UNITED STATES PATENT OFFICE

111,971

DESIGN FOR A CONFECTION

Harry W. Huse, Glendale, Calif.

Application April 8, 1938, Serial No. 76,377

Term of patent 14 years

To all whom it may concern:

Be it known that I, Harry W. Huse, a citizen of the United States, residing at Glendale, in the county of Los Angeles, California, have invented a new, original, and ornamental Design for a Confection, of which the following is a specification, reference being had to the accompanying drawing, forming a part thereof, and in which:

Fig. 1 is a side view of a confection showing my new design; and

Fig. 2 is a top plan view of the same.

As shown, the design comprises a lower dish-like object of edible material filled with a confection such as ice cream or the like, and covered on the top by a dome shaped cover, a portion of the confection being exposed between the two.

I claim:

The ornamental design for a confection, as shown and described.

HARRY W. HUSE.
